(57) **CLAIM**

The ornamental design for a boot jack, as shown and described.

DESCRIPTION

FIG. 1 is a front view of a bootjack.

FIG. 2 is a rear view of the boot jack.

FIG. 3 is a right side view of the boot jack.

FIG. 4 is a left side view of the boot jack.

FIG. 5 is a top view of the boot jack.

FIG. 6 is a bottom view of the boot jack; and,

FIG. 7 is a perspective view of the boot jack.

The broken lines illustrate portions of the boot jack that form no part of the claimed design.
